CIRCUIT BREAKER HAVING ARC EXTINGUISHING MEDIUM OF GRANULATED INSULATING MATERIAL WHICH INCLUDES A LUBRICANT TO DECREASE FRICTION BETWEEN ELEMENTS THEREOF

Henry Greber, 225 W. 80th St., Apt. 8-D,

New York, N.Y.

Filed Feb. 5, 1962, Ser. No. 171,098

1 Claim. (Cl. 200—149)

The object of this is to provide a circuit breaker of considerable interrupting capacity whose container is filled with granulated, or pulverized, non-flammable insulating material. The use of small pellets, sand or powder of glass porcelain, steatite and similar solid materials as fillers of circuit breakers opens new possibilities for the latter, by making them explosion-proof, which is particularly important in their application in locations with fire and explosion hazards.

The single figure shows a schematic sectional view of the breaker with solid filler. Numeral 1 designates the movable contact made of a longitudinally corrugated tube provided with point 2. The longitudinal grooves of the corrugation 20 are shown on the surface of tube 1. Movable contact 1 fits into the steady contact 3, made of a tube with holes 4 all along it. End of tube 3 has the form of a funnel 5. Finger contact 1 fits also into another contact 6, made of a tube with two funnel-shaped ends 7 and 8. All contacts are mounted within an insulating cylinder 9, which is partly filled with granulated or powdered insulating material 10. On the end of finger contact 1 is placed strain insulator 11, through which a mechanism (not shown) moves said finger contact 1 in and out of contact 3. The source of voltage 12 is connected by means of conductor 13 with steady contact 6, and by means of conductor 14 with useful resistance 15, which represents the energy consuming device, and is linked through conductor 16 with steady contact 3. Locknuts 17 and 18 and stud 19 serve for connection of conductor 16 to steady contact 3.

In operation of this circuit breaker, as soon as the mobile contact 1 is separated from the steady one 3, the space between them is instantaneously filled with the solid filler 10, and a possible arc between the separated contacts is extinguished or prevented. The finer the solid filler, the smaller is the gap between the separated contacts which is immediately filled with the granulated or powdered insulating material. There exists an obvious possibility of using a combination of the above named fillers, pellets and powder, or balls and small granules. Thus the interstices between the pellets and balls are completely filled with sand-shaped or powdered insulating material. Talcum powder, silicon liquid can be used for lubrication, in order to decrease friction between the insulating balls, pellets, and particles of insulating sand and powder, and also the friction between these particles and

2

the metallic contacts. To achieve a breaking up of the arc space into component ones, the pellets or granules can contain cores of metallic powder or such of semiconductors, for example of graphite.

5 As mentioned the present circuit breaker does away with the danger of explosions, always present in oil filled circuit breakers. At the same time the circuit breaker with solid filler has a greater short circuit interrupting capacity than the corresponding air circuit breaker. In 10 addition to this the solid filler dissipates better heat from the contacts at their passage by rated current. The present solid fillers can be used to facilitate current interruption in such devices as starters, contactors, rotary switches, relay contacts, collectors of electrical machines, for example for a D.C. machine with vertical collector immersed in a solid insulating medium of granulated consistency. The housing of knife switches with flicker blades can be filled with such medium. In the present circuit breaker the volume of its solid, granulated filler can be 15 much smaller than that of a corresponding insulating liquid. Therefore smaller breakers of higher current interrupting capacity than the ones now available can be built according to the present invention. Many modifications and variations of this circuit breaker can be made in 20 the spirit and within the scope of the following claim.

I claim:

A circuit breaker comprising, in combination; an enclosure substantially filled with a granulated insulating material; a tubular steady contact means having a flared 30 end, said tubular steady contact means being mounted in said enclosure and completely covered by said granulated insulating material; a movable finger contact means consisting of a pointed longitudinally corrugated tube mounted for cooperative engagement and disengagement 35 with said tubular steady contact means through its flared end, to open and close a circuit; holes in the wall of said tubular steady contact means to allow displacement of the granulated insulating material during engagement of the movable finger contact means with the tubular steady contact means; and said granulated insulating material including a lubricant consisting of talcum powder to decrease 40 friction between the granules of the granulated insulating material and between the granules and the movable and steady contact means.
